UNITED STATES PATENT OFFICE.

JOHN T. MASTERSON, OF HUNTINGTON, WEST VIRGINIA.

GAS-BURNER.

1,351,431.

Specification of Letters Patent. Patented Aug. 31, 1920.

Application filed July 10, 1919. Serial No. 309,820.

To all whom it may concern:

Be it known that I, JOHN T. MASTERSON, a citizen of the United States, residing at Huntington, in the county of Cabell and State of West Virginia, have invented certain new and useful Improvements in Gas-Burners, of which the following is a specification.

This invention relates broadly to gas burners, and has for its object to provide a gas burner of simple yet efficient construction and one wherein the fuel controlling ports are so positioned as to promote economy in fuel consumption without loss to the calorific output of the burner.

Another object of the invention rests in the provision of a gas burner wherein is embodied a main fuel conducting pipe member and a superimposed burner structure which includes a burner element having a pair of outlets formed therein, which outlets being in communication by means of a common passageway or chamber formed in the element, the inlet of said passageway being located directly over but spaced from a port formed in the main pipe member, whereby the fuel emitted from said port will be introduced into said passageway and in this manner will serve to supply the fuel necessities of both of said burner outlets.

For a further understanding of the invention, reference is to be had to the following specification and to the accompanying drawing, in which:

Figure 1 is a side elevation of the gas burner comprising the present invention.

Fig. 2 is a vertical longitudinal sectional view taken through one end of said burner, and,

Fig. 3 is a vertical transverse sectional view taken along the line 3—3 of Fig. 1.

Referring more particularly to the details of the invention, use is made of a gas burner A which, in its preferred embodiment, consists of a pair of spaced supports 1 and 2, and extending between said supports is a longitudinally disposed pipe member 3. The end of said pipe member which is threaded into the support 1 is closed, while the opposite end, carried by the support 2, is in communication with a supply pipe 4, also threadedly secured to the support 2. The opposite end of the pipe 4 carries a valve connection 5 which is suitably connected with a source of fuel supply. Obviously, by appropriate operations of the

connection 5, fuel may be admitted into the pipe member or kept out of the same. Longitudinally spaced ports 6 are formed at intervals throughout the length of the pipe member and through which fuel entering the pipe member is adapted to escape.

Located in superposed relation with respect to the pipe member is a burner structure B. The latter in this instance consists of an integral casting and embodies a horizontally extending shelf 7, which latter has its ends suitably enlarged as at 8, and screws 9 are adapted to pass through said enlarged ends to effect the securing of the shelf to the supports 1 and 2. Formed with the shelf 7 is a plurality of burner elements 10 which are suitably united by means of interconnecting web portions 11, and each of said burner elements is formed with an internally situated U shaped passageway or chamber 12. The latter have their central portions substantially widened and are formed to terminate in burner outlets 13, a pair of such outlets being provided to each of the elements 10. Communicating with the chambers or passageways 12 are inlet ports 14; the latter in this instance are formed in suitable projections depending from the shelf 7 and are of substantially conical formation, the enlarged lower ends of said ports being positioned immediately above the outlet port 6 of the pipe member 3, but in spaced relation from the latter so that upon the emission of gas or other fuel from the port 6, the fuel will be directed upwardly into the ports 14 and with the fuel stream there is entrained the desired proportion of atmospheric oxygen. This mixture is carbureted within the chambers 12, and is thence supplied to the communicating outlets 13.

It will be observed that the elements 10 are so proportioned that there will be one of said elements to each of the member ports 6, thus the fuel emitted from each of said ports 6 will supply a pair of the burner outlets 13 with their fuel necessities. By virtue of this construction and through the agency of liberal carburetion, very complete combustion will take place at the burner outlets 13, so that the fuel emitted from the pipe member 3 will be utilized with maximum efficiency. This construction results in the provision of a very economical burner and one wherein the waste of fuel is effectively precluded.

I claim:

A gas burner comprising a longitudinally extending pipe member having longitudinally spaced port openings formed therein,
5 a valved inlet connection disposed at one end of said member and the opposite end of said member being substantially closed, a burner structure mounted above said pipe member, said structure comprising a series
10 of substantially U shaped outlets having enlarged central portions and relatively reduced outlet portions, and a plurality of

projections depending from said burner structure, said projections being provided with a plurality of substantially funnel shaped ports, the latter having their lower extremities disposed immediately above and in registration with said member ports, and the upper restricted ends of said projecting ports terminating within the centrally enlarged portions of said outlets. 15 20

In testimony whereof I affix my signature.

JOHN T. MASTERSON.
